FIG. 4.

UNITED STATES PATENT OFFICE.

HARRY J. HICK, OF ALLIANCE, OHIO, ASSIGNOR, BY MESNE ASSIGNMENTS, TO THE McCASKEY REGISTER COMPANY, (INCORPORATED IN 1914,) OF ALLIANCE, OHIO, A CORPORATION OF OHIO.

FILING APPLIANCE.

1,253,375.

Specification of Letters Patent. Patented Jan. 15, 1918.

Application filed June 9, 1914. Serial No. 843,962.

To all whom it may concern:

Be it known that I, HARRY J. HICK, a citizen of the United States, residing at Alliance, in the county of Stark and State 5 of Ohio, have invented certain new and useful Improvements in Filing Appliances, of which the following is a specification.

The invention relates to a filing appliance for sales bills and other similar papers, 10 in which a plurality of bill holders are operatively mounted in a fireproof case comprising a rectangular base section and a similar cover section adapted to be swung upon the base section to incase the bill 15 holders when closed and to form a back for the same when opened.

In a former application, filed June 1, 1914, Serial No. 841,976, a filing appliance of this 20 type or character has been illustrated, described and claimed, in which a series of hinged bill holders and an index frame are pivoted to the rim of the rear end of the cover section of the case; and in a subsequent application filed June 8, 1914, Serial 25 No. 843,602, another filing appliance of this type or character has been illustrated, described and claimed, in which a second series of hinged bill holders are carried on a tray having operative connections with the index 30 frame for swinging the tray to and fro and means for guiding the forward end of the tray over and upon the forward rim of the base section, to bring the second series of 35 holders into operative position when the index frame is rotated into upright position.

The object of the present invention is to provide suitable supporting, operating and guiding means for such a second series of 40 holders, so that the same can be carried not only downward into the base section of the case, but rearward into the rear end thereof; and also to provide suitable guiding means for the forward end of the index frame so that the same need not rest or slide upon the 45 second series of holders.

The objects of the invention are attained by the preferred embodiment thereof, illustrated in the accompanying drawings, forming part hereof, in which—

50 Figure 1 is a side elevation of the case, showing the cover section closed downward upon the base section thereof;

Fig. 2, a side elevation section of the case, showing the location of the bill holders, the 55 index frame, and the supporting, operating, and

and guiding parts, when the cover section of the case is closed downward upon the base section thereof;

Fig. 3, a side elevation showing the cover section swung upward upon the rear end of the base section, and showing the location of the bill holders and index frame in this relation of the parts when the first series of bill holders are rotated into upright position with the index frame in reclined position and the second series of bill holders carried forward part way from the rear end of the base section; and

Fig. 4, a similar side elevation section, showing the index frame rotated and located 70 in upright position, and the second series of bill holders carried upward and forward into operating position with three of the holders rotated into upright position.

Similar numerals refer to similar parts 75 throughout the drawings.

The case is composed of the substantially similar rectangular bottom or base section 1, and the top or cover section 2, which are operatively connected together by means of 80 the guiding hinge brackets 3, one being located on each side of the rear end portion of the base section. The first series of bill holders 4, 4^a and 4^b, are hinged together at the lower rear ends, and the forward 85 holder 4^a is pivoted to the bearing brackets 5, secured on the rear end rim of the cover section; to which bearing brackets is also pivoted the rear end of the index frame 6, by means of the bracket 7. 90

The guiding hinge brackets 3 constitute a connection between the sections of the case by means of which the rear end of the cover is shifted forward to rest squarely upon the rear end of the base section with the top 95 of the cover section in alinement with the rear end of the base section, when the cover section is swung upward upon the base section as shown in Figs. 3 and 4; and so that the rear end of the cover section is shifted 100 rearward into alinement with the rear end of the base section, when the cover section is closed downward thereon as shown in Figs. 1 and 2. The details of these guiding hinge connections are illustrated and described in said former application, Serial No. 841,976, and will not be repeated herein.

The index frame 6 is provided on each side with a roller 8, journaled in a bracket 9, secured to the frame; and an inclined 110

track 10, is secured on each side wall of the base section, upon which tracks the frame rollers are adapted to travel to carry the frame downward within the base section, as shown in Fig. 2. The upper forward end of the tracks 10, are beveled or flattened substantially horizontally, upon which ends the rollers 8 may ride when the forward end of the frame is carried over the forward 10 rim of the base section, as shown in Fig. 3, so that the frame need not slide upon this rim.

The swinging tray 11, is provided for the second series of bill holders 4', 4^a' and 4^b', the rear end of which tray is carried by the lateral pivots 12, journaled in the lower ends of the pendent plates 13, secured to the rear end of the index frame; and the forward portion of the tray is normally supported on 20 the rollers 14, pivoted in the brackets 15, formed or secured on each side of the tray, which rollers ride upon the bottom of the case, when the tray is carried into the rear end thereof, as shown in Fig. 2, or upon 25 the curved tracks 16, secured to the sides of the base section, for carrying the forward end of the tray upward as shown in Fig. 3, to pass over and upon the forward rim of the base section as shown in Fig. 4.

30 The parts are so proportioned and arranged, that when the cover is closed downward upon the base section of the case, the tray and second series of holders are located in the lower rear portion of the base section 35 with the rollers 14 riding upon the bottom thereof; and the index frame is located in the upper rear portion of the base section, with its rollers 8 riding upon the inclined tracks 10 therein, and the first series of 40 holders extending upward into the cover section of the case as shown in Fig. 2.

When the cover section of the case is 45 swung upward upon the rear end of the bottom section thereof, the index frame is carried forward by its pivotal connections with the rear rim of the cover section; in which movement the rollers 8 ride upward upon the tracks 10, and carry the forward end of the frame upward to pass freely over and 50 upon the forward rim of the base section, as shown in Fig. 3.

At the same time, the rear end of the tray 11 is carried forward and upward by its pivotal connection with the pendent plates on 55 the rear end of the frame, during which movement the tray rollers 14 first ride upon the bottom of the case and then upward upon the curved tracks 16 into the substantially horizontal position shown in Fig. 3, 60 in the forward upward portion of the base section.

When the index frame 6 is rotated into upright position as shown in Fig. 4, where it may be locked by the latch 17, the pendent 65 plates, which together with the frame form

a bell crank lever fulcrumed on the rear end of the cover section, carry the rear end of the tray upward and forward, in which movement the tray rollers 14, riding on the curved tracks 16, carry the forward end of the tray upward, over and upon the forward rim of the base section of the case, as shown in Fig. 4; in which position the tray rollers may rise free of the tracks while the tray is sliding and resting upon the rim of the 75 base section.

The second series of bill holders 4', 4^a', and 4^b' are hinged together at the lower rear ends, and the forward lower holder 4^a', is pivoted at its hinged end to the rear end 80 of the swinging tray 11, as by means of the pivot bearings 18, provided thereon; and it is evident that when the swinging tray is carried upward and forward into the position shown in Fig. 4, these holders may be 85 rotated upward from their normal reclined position upon the tray, either singly or collectively, into upright position as shown in Fig. 4, giving access to the bills held by the spring clamps 19 mounted on the holders, in 90 a manner well known in this art.

When one or more of the second series of bill holders are rotated into upright position, it will be understood that the upright index frame serves as an abutment against 95 which the free end of the upper rear bill holder 4^b' rests and slides as the various holders are rotated upward and downward.

I claim:

1. A filing case including similar base and 100 cover sections with guiding hinge connections for swinging and shifting the cover section upon the base section, a frame having its rear end pivoted to the rear end of the cover section and having rollers on each side, 105 and inclined tracks on the sides of the base section upon which the rollers ride for carrying the forward end upward and freely over the forward rim of the base section when the frame is carried forward by the operation of the cover section upon the base section. 110

2. A filing case including similar base and cover sections with guiding hinge connections for swinging and shifting the cover section upon the base section, a frame pivoted at its rear end to the rear end of the cover section, and having pendent plates on its rear end, a tray pivoted at its rear end to the pendent plates and having rollers on 120 its sides normally riding on the bottom of the case, means for guiding the forward end of the frame upward and over the forward rim of the base section, and tracks for the tray rollers on the sides of the base section 125 for guiding the forward end of the tray over the forward rim of the base section when the cover section and frame are swung into upright position.

3. A filing case including similar base and 130

5 cover sections with guiding hinge connections for swinging and shifting the cover section upon the base section, a tray movable in the base section, a frame fulcrumed on the rear end of the cover section, and having a member connected to the tray for moving it to and fro when the frame is rotated, and tracks in the base section for guiding the forward end of the tray in its movements upwardly over the forward rim 10 of the base section.

15 4. A filing case including similar base and cover sections with guiding hinge connections for swinging and shifting the cover section upon the base section, a tray movably mounted in the base section, a bell crank lever fulcrumed upon the rear end of the cover section for moving the tray to and fro, and means for guiding the tray in its movements, upwardly over the forward rim 20 of the base section.

25 5. A filing appliance including a case of substantial length, a plurality of filing

leaves, a longitudinally movable tray for supporting the filing leaves, a bell crank lever operating on a fixed fulcrum and having one of its arms pivoted to the tray, for moving the tray to and fro, and means for guiding the forward end of the tray in its movements upwardly over the forward rim 30 of the case.

35 6. A filing appliance including a case of substantial length, a plurality of filing leaves, a longitudinally movable tray for supporting the filing leaves, a bell crank lever operating on a fixed fulcrum and having one of its arms pivoted to the tray, for moving the tray to and fro, and tracks in the case for guiding the forward end of the tray in its movements upwardly over the 40 forward rim of the case.
